UNITED STATES PATENT OFFICE.

WILLIAM L. BARRELL, OF LAWRENCE, MASSACHUSETTS.

LOOM.

1,207,124.

Specification of Letters Patent.

Patented Dec. 5, 1916.

Application filed December 21, 1912. Serial No. 737,967.

To all whom it may concern:

Be it known that I, WILLIAM L. BARRELL, a citizen of the United States, and resident of Lawrence, in the county of Essex and 5 State of Massachusetts, have invented certain new and useful Improvements in Looms, of which the following is a specification.

This invention relates to looms, and its 10 object is to automatically replenish the weft as often as occasion requires.

Of the accompanying drawings, which 15 illustrate one form in which the invention may be embodied: Figure 1 represents an elevation of the left end of a loom of which the lower end of the picker stick is broken away to avoid concealing essential parts of the present improvement. This figure shows the lay in its extreme rear position, where it 20 would sometimes be when the exchange of shuttles is made. Fig. 2 represents a view, partly in elevation and partly in section, including a part of the bobbin magazine, the lay, mechanism for transferring a full bobbin 25 to a shuttle, and mechanism for carrying the loaded shuttle from loading position to the shuttle box on the lay. Fig. 3 represents, in elevation, the forward part of the loom frame, and in section the shuttle carrier with a shuttle thereon in loading position, and a support for bracing the shuttle 30 carrier so as to sustain the stress upon the carrier when a full bobbin is inserted into the shuttle. Fig. 4 represents a perspective 35 view of mechanism for pushing the empty shuttle to loading position relatively to the carrier. Fig. 5 represents a vertical section through the lay and through the parts which form the shuttle box, including a removable 40 front and a shuttle ejector. Fig. 6 represents a section similar to Fig. 5, showing the same parts in different positions, the shuttle 45 front being lifted to permit ejection of the shuttle, the latter being shown ejected and supported by a receiver which lifts it to the 50 position indicated by dotted lines. Fig. 7 represents a perspective view of the shuttle receiver which is included in Fig. 6. Fig. 8 represents a top plan view of the carrier 55 which transfers the full shuttle from loading position to the shuttle box, and the empty shuttle from the receiver to loading

position. Fig. 9 represents a vertical section including the lay, the shuttle carrier in the act of placing a full shuttle thereon, and 55 the empty-shuttle receiver in its elevated position about to deposit the empty shuttle upon the carrier. Fig. 10 represents a front elevation of a portion of the shuttle carrier in loading position, including the support 60 which is affixed to the loom frame to sustain the stress of the loading mechanism. Fig. 11 represents an elevation of mechanism for actuating the loader.

The same reference characters indicate 65 the same parts wherever they occur.

The drawings show the present invention as applied to a loom of well known construction, made by the Stafford Company, of Readville, Massachusetts, and it may be 70 assumed that such construction and its operation are in accordance with standard practice of the aforesaid loom unless otherwise specified.

Referring first to Fig. 1, the frame of the 75 loom is indicated at 12, and the lay is indicated at 13. The crank shaft which operates the lay is indicated at 14, and the connecting rod at 15. A rockshaft which supports the lay is indicated at 16, and one of the 80 picker sticks at 17. The swords and the mechanism for operating the picker stick are omitted for the sake of simplifying the drawings.

The weaving mechanism of the loom is 85 driven by a suitable clutch which does not require illustration or description and which is controlled by a shuttle-changing stop-motion mechanism which causes disconnection of the clutch whenever the weft thread is 90 nearly exhausted. A well known element of a loom of this type is a cam shaft 18 which remains stationary in the position shown by Fig. 1 so long as the loom is weaving. This cam shaft is driven by well known clutch 95 mechanism (not shown) whereby one complete rotation is imparted to it for the purpose of operating mechanism which removes one shuttle from the lay and inserts a shuttle containing a full bobbin. This shuttle-replacing mechanism is substantially the same as that now in the aforesaid loom except in certain details which will be herein-after explained. It will be sufficient for 100

present purposes to state that the lay stops at or near the position shown by Fig. 1 when a change of shuttles is required, and that when the weaving mechanism is stopped, the cam shaft 18 is rotated once and then stops simultaneously with the starting of the weaving mechanism. During this single rotation of the cam shaft the necessary exchange of shuttles is made and then the loom is once more set in operation for weaving.

Referring now to Figs. 5 and 6, which show the several members at the left end of the lay which form a shuttle box, the 15 shuttle front is indicated at 19. This member remains in the position shown by Fig. 5 so long as the loom is weaving, but is lifted to the position shown by Fig. 6 whenever a change of shuttles is necessary. It is 20 affixed to a pair of arms 20 which arms are affixed with relation to each other and mounted to swing about a pivot member 21. This pivot member is mounted in brackets affixed to the lay, one of which brackets is 25 indicated at 22. An arm 23 extending to the rear and fixed with relation to the arm 20 is connected by a rod 24 with a lever 25 (see Fig. 1), near the bottom of the loom. This lever is mounted upon a fulcrum 26 30 and is provided with a roll 27 which is adapted to be engaged by a cam 28 on the shaft 18. The shuttle front and the connections just described are normally locked in the position shown by Figs. 1 and 5. A 35 spring 29, the upper end of which is connected to one of the arms 20 and the lower end of which is connected to one of the brackets 22 affixed to the lay, exerts a downward pull on the arm 20 and consequently 40 exerts an upward pull on the operating lever 25. When the cam 28 depresses the lever 25, the shuttle front is lifted to the position shown by Fig. 6, and while it is in this position the shuttle 29 is ejected from 45 the lay. This mechanism for lifting the shuttle front, and the ejecting mechanism about to be described are both well known parts of the Stafford loom.

The ejecting mechanism is operated by 50 the mechanism just described. An ejector is indicated at 30. It is mounted upon an oscillatory carrier 31 which is mounted upon a pivot member 32. The pivot member is supported by a fixture 33 mounted upon the 55 lay. The carrier 31 has a forward extension in which is mounted a setscrew 34. This setscrew is so located as to be engaged and lifted by a portion of one of the arms 20, and when so lifted the ejector is moved 60 from the position shown by Fig. 5 to that shown by Fig. 6. The ejector moves the shuttle from the lay, toward the front of the loom. A spring 35 connected in suitable manner to the ejector, returns the latter to

the position shown by Fig. 5, when the shuttle front 19 is lowered.

In my invention the ejecting of the shuttle 65 29 transfers the shuttle to a receiver 36, shown best by Fig. 7. This receiver normally occupies the position shown by Figs. 70 1, 5 and 6. It is connected to the lay so that it swings back and forth with the lay when the loom is weaving, and is always in position to receive an ejected shuttle excepting when an exchange of shuttles is 75 being made, at which time the receiver is lifted to the position indicated by Figs. 6 and 9, prior to the transferring of another shuttle into the shuttle box. The function of this receiver is to receive and place the 80 ejected shuttle upon the carrier which inserts the new shuttle. The receiver comprises two shuttle-supporting clips 37 which have lips 38 for the purpose of preserving the lateral position of the shuttle so that it 85 will be deposited in the desired position upon the carrier hereinafter explained. The supporting clips 37 are spaced a considerable distance from each other and they 90 engage the shuttle near the ends of the latter. A clear unobstructed space is left between these supporting clips, for the shuttle carrier when the receiver deposits the ejected shuttle upon the carrier, as will be better understood after further description. 95 The receiver also has clips 39 whose function is to preserve the endwise relation of the shuttle. These clips have converging extremities 40 whose function is to guide the shuttle into the receiver when the shuttle is being ejected. If the shuttle is not in the desired endwise position when it is ejected, the converging portions 40 will impart the necessary endwise movement to cause the shuttle to enter the receiver and 100 occupy the desired position therein. The frame 36 of the receiver is so formed that a shuttle may pass horizontally through it beneath the clips 37, the distance between the upright portions 41 of the frame being 105 considerably more than the length of the shuttle, and the distance between the bottom of the frame and the supporting clips 37 being considerably more than the depth of the shuttle. While the receiver is elevated 110 to the position shown by Fig. 9 and shown by dotted lines in Fig. 6, the new shuttle passes through the frame of the receiver and does not engage the same.

The receiver is mounted upon the upper 115 end of a swinging arm 42 whose lower end is pivotally connected at 43 to a lever 44. The fulcrum 26 of the lever 25 serves also as the fulcrum for the lever 44. A roll 45 mounted on the lever 44 cooperates with a cam 46 120 on the cam shaft 18. This cam lifts the arm 42 and the shuttle receiver, and the arm is guided by a stud 47 carried by a bracket 48

affixed to the lay. The stud extends through a slot 49 in the arm, and the faces of the arm which define this slot are so disposed as to cause the shuttle to move forwardly when 5 moving upwardly, and move rearwardly when moving downwardly. This enables the empty shuttle to rise without striking the shuttle front 19. The weight of the parts just described is sufficient to cause them to 10 descend when the cam permits. The pivot stud 43 which connects the arm 42 and the lever 44 is disposed close to and in vertical alinement with the axis of the shaft 16 about which the lay swings, so that the relative 15 movement of the receiver and the lay when the loom is weaving will be negligible. The receiver just described, and its operating mechanism, is a new element in the present invention.

20 The bobbin magazine indicated as a whole at 50 in Figs. 1 and 2 is of well known construction, and for this reason it will not be necessary to describe it, except in a general way. This magazine is rotary, the rotatable 25 element being indicated as a whole at 51, and the stationary frame of the magazine at 50. The rotatable element is mounted upon a shaft 52, and the direction of rotation is indicated by an arrow in Fig. 1. Full bobbins are indicated in Fig. 2 at 53. The rotatable element is rotated step by step so as to carry the bobbins successively against a stop and guide 54. Each bobbin as it moves against the stop member comes under a lever 30 55 which for convenience may be termed a "loader", since its function is to push the bobbin downwardly out of the magazine and into a shuttle supported beneath it. The shuttles and bobbins and the loader 35 shown are well known and require no description other than a statement that the bobbin is held in the shuttle by well known means and that the operation of forcing a full bobbin into the shuttle at the top forces the empty bobbin out at the bottom. The loader 55 receives its loading motion from mechanism hereinafter explained, and it is returned to the position shown by Fig. 2 by a spring 56. The loader carries a pawl 57 40 which engages teeth 58 on the rotatable element of the magazine in such manner that the rotatable element is moved one step by the upward movement of the loader. This operation is in no way different from the 45 operation of well known magazines now in use.

50 Figs. 1, 2 and 3 illustrate a shuttle 59 in loading position. The shuttle is supported in this position by a carrier 60. This carrier is affixed to a swinging lever 61 whose fulcrum 62 is located directly above and close to the rockshaft 16 which carries the lay. Referring to Fig. 1, the fulcrum 62 is 55 behind and concealed by the lower end of the

arm 42 and pivot 43. The function of the 65 carrier 16 is to carry a loaded shuttle to the lay to replace the ejected shuttle, then to carry the ejected shuttle to the magazine, and support the empty shuttle during the loading operation. The proximity of the 70 fulcrum 62 to the axis about which the lay swings causes the shuttle on the carrier to describe an arc nearly concentric to the arc described by the lay. The movement of the carrier when transferring a loaded shuttle 75 from the magazine to the lay is effected by a spring 63, and this movement is controlled by the surface 64 of a cam 65 on the shaft 18, the arm 61 having a roll 97 which engages the cam. The return movement of the car- 80 rier is effected by the surface 66 of this cam. The use of this carrier for taking an ejected shuttle to the bobbin magazine is new and there are certain details concerning its construction which are new. Its function in 85 transferring a loaded shuttle to the shuttle box is old. Its construction is new in that it is formed with an opening 67 through which the empty bobbin may drop when a full bobbin is placed in the shuttle. The structural 90 details of the carrier are shown best by Figs. 8, 9 and 10. Its upper surface, indicated at 68 in Figs. 8 and 9, supports the shuttle during the loading operation of the latter. The position of the shuttle when being loaded is 95 indicated by dotted lines in Fig. 8, and the shuttle as shown in section in Fig. 2 is in loading position. The shuttle which is ejected from the shuttle box and raised by the receiver is deposited upon the loading surface 68 of the carrier, the path of the empty shuttle when being thus deposited being indicated in Fig. 9 by dotted lines a, a. The carrier has a flange 69 and spring clips 70 which preserve the lateral position of the 100 shuttle when it is on the loading surface. The movement of the receiver 36 is such as to deposit the shuttle between this flange and the clips. When the carrier is in loading position, one of its ends (see Fig. 10) rests 110 upon a stationary support 120 which is affixed to the frame 12 of the loom. The function of this support 120 is to sustain the downward stress upon the carrier when the loader is forcing a full bobbin into the shuttle. This support is also shown by Fig. 3. In this figure it will be observed that the upper surface of the fixed support and the contacting surface of the carrier are curved. The curvature is concentric with relation to 120 the axis 62 about which the carrier moves.

When an exchange of shuttles is to be made, the loaded shuttle 59 is first transferred from the surface 68 of the carrier to a pair of supporting fingers 71 which project toward the lay. The transfer of the shuttle to these fingers is effected by moving the carrier away from the lay and by 125

1
4
preventing such movement of the shuttle, this movement of the carrier relatively to the shuttle causing the fingers 71 to move under the shuttle, whereupon the shuttle 5 drops slightly until it rests upon the fingers. This slight movement of the carrier away from the lay is effected by the surface 72 of the cam 65, and movement of the shuttle away from the lay is prevented at this time 10 by a fixed bar 73. This bar is in the present instance affixed to the frame 50 of the bobbin magazine, and its ends 74, as shown by Figs. 1 and 3, embrace the ends of the shuttle so as to prevent endwise creeping of the latter. The spring slips 70 may be easily flexed, and they are depressed by their engagement with the shuttle when the carrier 15 60 is moved to transfer the shuttle to the fingers 71. When the shuttle rests upon the fingers 71 its front side is engaged by shoulders 75 on the carrier and is moved positively into the shuttle box on the lay by these shoulders while being supported by the fingers.

Figs. 1, 2 and 4 show mechanism for moving the shuttle 59 against the fixed bar 73, for the purpose of insuring the desired position of the shuttle for loading. This mechanism comprises a pusher 76 which is shown in the form of a rod. It is carried by a bell-30 crank lever 77 which is mounted upon the exterior of the magazine frame 50. The fulcrum of this lever is indicated at 78. A rod 79 extends from the lever 77 to a pin 80 which is carried by a lever 81. The fulcrum 35 of the lever 81 is indicated at 82 in Fig. 1. The upper surface of the lever 81 is for the most part curved, but it has an inclined shoulder 83 which is in effect a cam surface. This surface is disposed to be engaged by a 40 roll 84 mounted upon the carrier lever 61. When the carrier moves from the lay toward the magazine with a shuttle which has just been ejected from the shuttle box, the roll 84 strikes the cam surface 83 when the carrier 45 has nearly reached loading position. The free end of the lever 81 is depressed against the tension of a spring 85 (Fig. 1), which spring is connected at its upper end to a fixture on the frame 12 and at its lower end to the 50 pin 80 carried by the lever. The downward movement of the lever 81 causes the pusher 76 to move toward the fixed bar 73 and thus push the shuttle against the bar if it is not already in that position. The subsequent 55 forward movement of the carrier whereby the loaded shuttle is transferred to the fingers 71 does not cause any further movement of the pusher 76, because the surface 86 which at this time is engaged by the 60 roll 84 is concentric with relation to the axis of the stud 62 upon which the carrier is mounted. The pusher therefore remains in the position shown by Figs. 1 and 2, and prevents tipping movement of the shuttle 65 during the transfer from the surface 68 to

the fingers 71. When the shuttle has dropped to the fingers 71, its top surface is below the pusher, so that it will pass under the pusher in moving toward the lay. When the roll 84 rides over the surface 83 of the lever 81 in moving toward the rear of the loom, the spring 85 lifts the lever 81 and swings the pusher toward the rear and upwardly so that the pusher will not obstruct the path of the shuttle which will be carried from the 75 lay to the magazine.

Upon the completion of the shuttle-exchanging operation, the power for operating the loom for weaving is automatically connected and the power for driving the cam 80 shaft 18 is disconnected. As previously stated, the clutches for connecting and disconnecting the power in these two respects are well known and are not shown by the accompanying drawings. Fig. 1, however, includes cam-operated mechanism for moving a controller which sets the aforesaid clutches. For this purpose the cam shaft is provided with a starting cam 87 which actuates a lever 88 whose fulcrum is indicated at 26. 90 This lever has an arm 89 whose upper end engages a collar 90 affixed to a starting rod 91. The forward end of this rod is pivotally connected to a lever 92. The lever is affixed to a rockshaft 96 which extends across the 95 front of the loom to the opposite end, where it is connected with the above-mentioned clutch mechanisms. When the parts are in the position shown by Fig. 1, the power for operating the loom has just been disconnected, 100 and the power for operating the cam shaft has just been connected, but the cams are shown in the position which they occupy when at rest. When the exchange of shuttles has been made, the cam 87 moves the 105 lever 88 in such manner as to move the rod 91 toward the rear of the loom. This movement is utilized for the new purpose of operating the loader 55 so that a full bobbin will be placed in the shuttle 59, and the shuttle so loaded will be ready to be placed in the loom when the next exchange of shuttles is necessary. For the purpose of operating the loader, the lever 92 is provided with an arm 93 which is connected to the loader by a 110 link 94. This connection effects a downward or loading movement of the loader when the lever 92 is actuated to start the loom.

A brief summary of the operations in the order in which they occur is as follows: Assuming that a change of shuttles is required to replenish the weft, the weaving mechanism is automatically stopped in accordance with the usual practice when the lay is toward the rear, as shown by Fig. 1. This operation releases the clutch-controlling mechanism and permits the loader 55 to rise. If there is no special spring for moving the clutch-controlling mechanism it will be moved by the spring 56 which lifts the 115 120 125 130

loader (see Fig. 2), this spring exerting an upward pull sufficient to move the starting lever 92 to the position shown. The cam shaft 18 then begins to turn in the direction indicated by an arrow in Fig. 2, and the first movement imparted by the cams is that which transfers the loaded shuttle from the upper surface of the carrier to the fingers 71, and during this movement the cam 28 lifts the front 19 of the shuttle box on the lay and ejects the shuttle 29. The carrier with the loaded shuttle then starts toward the lay, and at the same time the receiver which supports the ejected shuttle begins to rise, so that the carrier with the loaded shuttle may pass through the open frame of the receiver and deposit the loaded shuttle in the shuttle box. Inasmuch as the carrier 60 is moved toward the lay by a spring, the co-operative relation of the carrier and the lay will not be disturbed by any variation in the position at which the lay stops, because the carrier will always move toward the lay until the surface 95 of the carrier is against the lay, as shown by Fig. 9. Consequently the co-operative relation of the carrier and receiver 36 will not be disturbed, because the position of the receiver is likewise varied by the position of the lay. When the carrier 60 has moved to the position shown by Fig. 9, the shuttle front 19 is dropped to the position shown by Fig. 5, thus confining the new shuttle. The receiver 36 now descends and deposits the ejected shuttle upon the surface 68 of the carrier, and the receiver continues to descend sufficiently to enable the shuttle to pass over it when the carrier moves forward toward the magazine. The carrier now moves forward to place the old shuttle in loading position, and as the shuttle is about to come to rest in loading position the pusher 76 is operated to push the shuttle against the fixed abutment 73. The cam 87 then actuates the starting mechanism, and this in turn actuates the loader which places a full bobbin in the shuttle, the full bobbin ejecting the partially or completely exhausted bobbin already in the shuttle. About this time the power is connected for setting the loom in operation and is disconnected from the cam shaft 18.

Having thus explained the nature of my said invention and described a way of constructing and using the same, although without attempting to set forth all the forms in which it may be made or all the modes of its use, what I claim is:

1. The combination with the weaving mechanism of a loom, of a bobbin magazine, means adapted to transfer a spent shuttle from said weaving mechanism to a bobbin-receiving position while said weaving mechanism is at rest, and means ar-

ranged to transfer a bobbin from said magazine to the shuttle in said position.

2. The combination with the weaving mechanism of a loom, of a bobbin magazine, means arranged to transfer a bobbin from said magazine to a shuttle outside said weaving mechanism, and means adapted to transfer the loaded shuttle from bobbin-receiving position to said weaving mechanism while the latter is at rest. 70

3. The combination with the shuttle box of a loom, of a bobbin magazine, means for transferring a bobbin from said magazine to a shuttle outside said shuttle box, and means for interchanging said shuttle and a shuttle in said shuttle box while the shuttle box is at rest. 75

4. The combination with the shuttle box of a loom, and a crank shaft for reciprocating the same, of a bobbin magazine, means 80 for transferring a bobbin from said magazine to a shuttle outside said shuttle box, and means operable while said crank shaft is at rest for interchanging a spent shuttle in said shuttle box and a loaded shuttle 90 outside the shuttle box.

5. The combination with the shuttle box of a loom, of a bobbin magazine, a shuttle carrier movable back and forth from the magazine to the shuttle box, means for 95 actuating said carrier to carry a loaded shuttle from the magazine to the shuttle box, means for actuating the carrier to carry an empty shuttle to the magazine, and means for transferring a bobbin from 100 the magazine to the empty shuttle.

6. The combination with the shuttle box of a loom, of a bobbin magazine, a shuttle carrier, means arranged to move said carrier to transfer a loaded shuttle to said 105 shuttle box and to transfer an empty shuttle to bobbin-receiving position relatively to said magazine, and means arranged to transfer a full bobbin from said magazine to said empty shuttle. 110

7. The combination with the shuttle box of a loom, of a bobbin magazine and means for operating the same to feed a bobbin, a shuttle carrier movable back and forth from said magazine to said shuttle box, 115 means for actuating said carrier to transfer an empty shuttle from the shuttle box to said magazine for loading, and means for actuating said carrier to return the loaded shuttle to the shuttle box. 120

8. The combination with the shuttle box of a loom, of a bobbin magazine, a shuttle carrier movable back and forth from the magazine to the lay, means for ejecting an empty shuttle from the shuttle box, means 125 for receiving the ejected shuttle and delivering the same to the shuttle carrier, said receiving and delivering means being arranged to carry the shuttle clear of the path of said shuttle carrier. 130

9. The combination with the weaving mechanism of a loom, of a bobbin magazine, means for supporting an empty shuttle adjacent the magazine in position to receive a bobbin from the latter, a loader for transferring a bobbin from the magazine into the empty shuttle, a movable member for applying the power to operate the weaving mechanism, mechanism for actuating said movable member, and means connecting said movable member and said loader for actuating the latter to transfer a bobbin to the shuttle.

10. The combination with the shuttle box of a loom, of a bobbin magazine, a shuttle carrier movable back and forth from the magazine to the lay for supporting an empty shuttle adjacent the magazine in position to receive a bobbin therefrom, said carrier having means for supporting a full shuttle for carrying the same to the shuttle box, yielding means mounted on said carrier for holding the shuttle in bobbin-receiving position on the carrier, an abutment for engaging the shuttle, means for transferring a bobbin from the magazine to the shuttle, and means for moving the shuttle carrier relatively to the said abutment for transferring the loaded shuttle from bobbin-receiving position to said shuttle-supporting means which carries the loaded shuttle to the shuttle box, said yielding means being adapted to be displaced by engagement with the shuttle when the carrier is moved to transfer the shuttle on the carrier as aforesaid.

11. The combination with the shuttle box of a loom, of a bobbin magazine, a shuttle carrier movable back and forth from the magazine to the shuttle box, said carrier having provisions for carrying a loaded shuttle from the magazine to the shuttle box and provisions for carrying an empty shuttle to the magazine, means for transferring a bobbin from the magazine to the empty shuttle, and means for transferring the loaded shuttle from loading position on said carrier to said provisions for carrying the loaded shuttle to the shuttle box.

12. The combination with the shuttle box of a loom, of a bobbin magazine, a shuttle carrier movable back and forth from the magazine to the shuttle box, said carrier having provisions for carrying a loaded shuttle from the magazine to the shuttle box and provisions for carrying an empty shuttle to the magazine, means for ejecting an empty shuttle from the shuttle box, means for transferring the ejected shuttle to said carrier, and means for transferring a bobbin from the magazine to the empty shuttle.

13. The combination with the shuttle box of a loom, of means for ejecting an empty shuttle therefrom, a receiver for the ejected shuttle, loading means for inserting a full

bobbin in a shuttle, and means for transferring the ejected shuttle from said receiver to said loading means for loading, said transferring means being operable for transferring the loaded shuttle from loading position to said shuttle box.

14. The combination with the shuttle box of a loom, of means for ejecting an empty shuttle therefrom, means movable with said shuttle box for supporting the ejected shuttle, means for inserting a full bobbin into a shuttle, and means for transferring the shuttle from said supporting means to said bobbin-inserting means.

15. The combination with the shuttle box of a loom, of means for ejecting an empty shuttle therefrom, means movable with said shuttle box for supporting the ejected shuttle, means for inserting a full bobbin into a shuttle, and means for transferring said shuttle from said supporting means to said bobbin-inserting means, said shuttle-supporting means being movable relatively to said shuttle box for transferring said shuttle to said transferring means.

16. The combination with the shuttle box of a loom, of means for ejecting an empty shuttle therefrom, means movable with said shuttle box for supporting the ejected shuttle, means for inserting a full bobbin into a shuttle, and means for transferring said shuttle from said supporting means to said bobbin-inserting means, said supporting means being movable relatively to said shuttle box for transferring said shuttle to said transferring means, said transferring means having provisions for transferring said shuttle from said bobbin-inserting means to said shuttle box.

17. The combination with the shuttle box of a loom, of means for ejecting a shuttle therefrom, a receiver for the ejected shuttle, means for operating said receiver to raise the ejected shuttle above the shuttle box, means for carrying a full shuttle to said shuttle box, said receiver-operating means being adapted to lower said receiver to place the ejected shuttle upon said carrying means, and means for loading a full bobbin into a shuttle outside the shuttle box, said shuttle-carrying means being adapted to carry the ejected shuttle to said loading means.

18. The combination with the shuttle box of a loom, of a shuttle receiver movable forward and back with said shuttle box, means for ejecting a shuttle from said shuttle box to said receiver, means for carrying another shuttle to said shuttle box, means for operating said receiver to place the ejected shuttle upon said carrying means, and means for loading a full bobbin into a shuttle, said carrying means being operable for carrying the ejected shuttle to said loading means.

19. The combination with the shuttle box of a loom, of mechanism for interchanging

25. The combination with the shuttle box of a loom, of a bobbin magazine, means for transferring an empty shuttle from the shuttle box to the magazine, movable means for engaging said shuttle to hold the same in bobbin-receiving position, said holding means being operable by said transferring means, and means for transferring a bobbin from the magazine into the shuttle. 70
26. The combination with the shuttle box of a loom, of a bobbin magazine, means for transferring an empty shuttle from the shuttle box to the magazine, an abutment for engaging the empty shuttle to determine its bobbin-receiving position, means movable to and from the shuttle for holding the shuttle against said abutment, and means for transferring a bobbin from the magazine into said shuttle. 75
27. The combination with the shuttle box of a loom, of a bobbin magazine, a shuttle support, means arranged to transfer a full bobbin from said magazine to a shuttle on said support, and means arranged to move said support to transfer said shuttle and bobbin to said shuttle box and to transfer an empty shuttle to bobbin-receiving position relatively to said magazine. 80
28. The combination with the shuttle box of a loom, of a bobbin magazine, a shuttle support, means arranged to transfer a full bobbin from said magazine to a shuttle on said support, and means arranged to move said support to transfer the loaded shuttle to said shuttle box. 95
29. The combination with the shuttle box of a loom, of means arranged to transfer an empty shuttle from said shuttle box, and means arranged to insert a full bobbin into such empty shuttle outside said shuttle box, said transferring means including means arranged to carry the shuttle to and from bobbin receiving position. 100
30. A loom comprising weaving mechanism and shuttle-transferring mechanism adapted to operate independently of each other, a bobbin magazine, said shuttle-transferring mechanism being adapted to transfer a spent bobbin from the shuttle-box of said weaving mechanism to a bobbin-receiving position outside said shuttle box while said weaving mechanism is at rest, and means arranged to transfer a bobbin from said magazine to a shuttle in said position. 110
31. A loom comprising weaving mechanism and shuttle-transferring mechanism adapted to operate independently of each other, a bobbin magazine, and means arranged to transfer a bobbin from said magazine to a shuttle outside the shuttle-box of said weaving mechanism, said shuttle-transferring mechanism being adapted to transfer the loaded shuttle from bobbin-receiving position to said shuttle-box while said weaving mechanism is at rest. 115
32. The combination with the shuttle box of a loom, of means for loading a full bobbin into a shuttle outside said shuttle box, means for supporting a shuttle for loading, and coöperative devices for engaging a shuttle in loading position to prevent displacement of the shuttle, one of said devices being movable from shuttle-engaging position to permit transferring the shuttle, said supporting means being movable for transferring the loaded shuttle to said shuttle box. 120
33. The combination with the shuttle box of a loom, of means for loading a full bobbin into a shuttle outside said shuttle box, means for supporting the shuttle for loading, said supporting means being movable for carrying the loaded shuttle to said shuttle box and for carrying a spent shuttle to loading position, coöperative devices for engaging a shuttle in loading position to prevent displacement of the shuttle, one of said devices being movable from shuttle-engaging position to release the shuttle, and means for actuating said movable device to press the shuttle against the other one of said coöperative devices. 125
34. The combination with the shuttle box of a loom, of means for loading a full bobbin into a shuttle outside said shuttle box, means for carrying a spent shuttle to loading position and for carrying a loaded shuttle to said shuttle box, and coöperative devices for engaging a shuttle in loading position to prevent displacement of the shuttle, one of said devices being movable to release the shuttle, and means operable by said carrying means for causing said movable device to press the shuttle against the other one of said devices. 130

32. A loom comprising weaving mechanism and shuttle-changing mechanism adapted to operate independently of each other, a bobbin magazine, and means arranged to transfer a bobbin from said magazine to a shuttle outside the shuttle-box of said weaving mechanism, said shuttle-changing mechanism being adapted to interchange such

shuttle and a shuttle in said shuttle-box while said weaving mechanism is at rest. 10

In testimony whereof I have affixed my signature, in presence of two witnesses.

WILLIAM L. BARRELL.
